PRODUCTION OF ANTIKNOCK GASOLINE

Louis H. Fitch, Jr., Bartlesville, Okla.; The First National Bank in Bartlesville, a national banking corporation, administrator of said Louis H. Fitch, deceased, assignor to Phillips Petroleum Company, a corporation of Delaware

Application October 8, 1934, Serial No. 747,459

3 Claims. (Cl. 196—10)

This invention relates to the pyrolysis of volatile hydrocarbons to produce therefrom motor fuels of high antiknock value.

It is well known that normally gaseous hydrocarbons other than methane, when cracked at any pressure under suitable conditions of time and temperature, will yield liquid hydrocarbons partly of the motor fuel boiling range. Processes for accomplishing this purpose are normally classified as high or low pressure processes, though no sharp dividing line as to pressure may be said to exist. In general, the low pressure processes are characterized by the formation of liquid hydrocarbons primarily of the aromatic series, and the high pressure processes by the formation of liquid hydrocarbons of other series.

My invention comprises a process wherein inter-related high and low pressure cracking steps are used to convert hydrocarbons of a boiling range not substantially higher than that of gasoline into a superior anti-knock motor fuel, using therefor simple and inexpensive apparatus, and producing as byproducts in substantial quantities only the fixed gases, methane and hydrogen.

More specifically, it comprises a process in which the liquids attained from a high pressure cracking process are used to supply charging stock to a low pressure process, and simultaneously to scrub aromatic hydrocarbons and recycle stock from the gases effluent from the low pressure process, with the production of a motor fuel of high anti-knock value.

The operation of my process will be evident from the following description, taken in conjunction with the accompanying drawing, of which Figure 1 is a diagrammatic view of a plant suitable for carrying out my process. In this drawing, 1 is a tubular heater, or heater and reaction chamber, designed for operation at pressures up to 1000 pounds per square inch or more, discharging through the pressure reduction valve 2 and the cooling coil 3 into the high pressure fractionator 4. From this fractionator are drawn off fixed gas and normally liquid hydrocarbons, at the top and bottom respectively. In addition, above the point of entry of the gases and liquid from the cooler 3, there is withdrawn a side stream 5, comprising principally normally gaseous hydrocarbons of from two to four carbon atoms per molecule, and this side stream passes through the valve 6 into the low pressure cracking unit 7, said low pressure unit being either a tube coil or a tube coil and reaction chamber. The cracked gases from this low pressure unit then pass through the cooler 8 and the compressor 9 back

into the fractionator 4, entering therein at a point substantially below the point of withdrawal of the side stream 5. The usual devices for refluxing and reboiling will be used with the fractionator, but are not shown in the drawing for the sake of simplicity. For most efficient operation, some measure of refrigeration at the top of the column 4 will be provided.

Many slight modifications of this apparatus will immediately be evident to one skilled in the art. 10 For example, the tube coils of the high and low pressure units may be incorporated in the same furnace setting, and a diagram of a furnace so constructed is shown in Fig. 2, in which A is the low pressure, high temperature cracking coil, exposed to the highest temperature in the radiant section of the furnace, and B is the high pressure coil, heated by the combustion gases in a convection section of the furnace, the temperature of the coil B being adjusted independently of A 15 by the use of dampers. 20

Heat exchangers may also be employed where economy dictates, but are not claimed as any part of my invention.

I may charge to my process any hydrocarbon liquid (except methane) which does not boil substantially above the boiling range of gasoline. Specifically, I may charge butane, natural or oil refinery gas fractions substantially free from methane, or straight run gasoline to be reformed to improve its antiknock rating. With this latter charging stock, the volume of vapors going to the low pressure cracking stage would be relatively small, and could be increased by admission of normally gaseous hydrocarbons through valves 10 30 or 11 of Figure 1. 35

Examples of the operation of my process are as follows:

Example 1

A vapor recovery plant fraction consisting principally of butane and butylene in about equal proportions is charged to the high pressure still 1, and cracked or polymerized at a pressure of 2000 pounds per square inch and a temperature of 870° F. The cracked products, which will contain most of the butane in the charging stock, are run into the fractionator 4, operating at 325 pounds per square inch, with a low temperature at the column top. Fixed gases, such as methane, are liberated from the top of the fractionator and the unchanged butane and other normally gaseous hydrocarbons are removed as a side stream, and cracked in the low pressure unit 7, at a temperature of about 1400° F. or 1500° F. and a pressure of 50 55

200 lbs. per square inch or less. The products of this low pressure reaction, consisting principally of fixed gases and aromatic hydrocarbons, are cooled, scrubbed to remove tar, compressed 5 to the pressure of the fractionator, and injected therein at a point substantially below that at which the side stream was taken off. The liquid product taken off the bottom of the fractionator is principally of the gasoline boiling range, and 10 contains 20-40 percent of aromatic hydrocarbons. It may be treated with suitable treating agents, and distilled to yield a stable gasoline of very high antiknock value.

15 *Example 2*

Straight run gasoline is charged to the high pressure unit 1 at a pressure of 1000 pounds per square inch, and cracked at a temperature of 950° F. The products are injected into the fractionator, 20 and the side stream from the fractionator is cracked as in the previous example. The effluent vapors from the low pressure cracking coil are cooled by the injection of cold butane through the valve 11, and compressed and injected into the 25 fractionator as in the previous example. The yield obtained is approximately equal to the volume of straight run gasoline charged, but the antiknock value has been appreciably increased.

30 *Example 3*

Butane is charged to the high pressure coil and cracked at 3000 pounds per square inch pressure and a temperature of 1030° F. The products of the reaction are all discharged into the fractionator 4, operating at a pressure of 300 pounds per square inch. Subsequent operation is the 35 same as in Example 1.

While the foregoing examples have been given as illustrations, I do not wish to be limited thereto, as I may charge to my process any hydrocarbons, except methane, having a boiling range not appreciably above that of gasoline.

40 I claim no novelty for a two stage cracking process, nor for the specific cracking conditions maintained in either stage. For the conduct of my process, it is only necessary that the pressure in the first cracking stage be greater than that maintained in the fractionator, and the pressure in the second stage on the order of, or lower than that maintained in the fractionator. It is evident, 45 of course, that the insertion of the pump 9 in the line 5 of Figure 1 of the attached drawing in place of its present position, would not constitute a departure from the spirit of my invention.

50 What I claim is:

55 1. A hydrocarbon conversion process which comprises subjecting a stream of light aliphatic hydrocarbons, substantially all of which boil below the maximum boiling point of gasoline and above the boiling point of methane, to conversion 60 conditions at high temperature and relatively high superatmospheric pressure, passing all the products of said conversion to a separating zone maintained under a pressure relatively high but lower than that used in the aforesaid conversion, 65 separating in said zone fixed gas, gasoline and heavier liquids, and a fraction intermediate between said gas and gasoline, discharging the fixed gas from the process, withdrawing said intermediate fraction and subjecting it to conversion con-

ditions wherein the temperature is relatively high and the pressure relatively low and wherein these conditions are maintained for a time sufficient to produce principally fixed gases and aromatic hydrocarbons, cooling the products of this latter conversion and increasing the pressure thereon and discharging them into the said separating zone at a point substantially below the point of withdrawal of the aforesaid intermediate fraction, separating the products of this latter conversion into fractions similar to those of the former conversion and discharging the combined fractions from said separating zone.

2. A hydrocarbon conversion process which comprises subjecting a stream of light aliphatic hydrocarbons, substantially all of which boil below the maximum boiling point of gasoline and above the boiling point of methane, to conversion conditions at high temperature and relatively high super-atmospheric pressure, passing the 15 products of said conversion to a separating zone, separating in said zone a fraction consisting principally of gasoline and heavier liquids and a fraction consisting principally of hydrocarbons containing from two to four carbon atoms in the molecule, subjecting said last-mentioned fraction to conversion conditions wherein the temperature is relatively high and the pressure relatively 20 low and wherein these conditions are maintained for a time sufficient to produce aromatic hydrocarbons, cooling the products of this latter conversion and increasing the pressure thereon and discharging them into the said separating zone at a point below the point of withdrawal of the 25 fraction consisting principally of hydrocarbons containing from two to four carbon atoms in the molecule, separating the products of this latter conversion into fractions similar to those of the former conversion and discharging the combined 30 fractions from said separating zone.

3. A hydrocarbon conversion process which comprises subjecting a stream of light aliphatic hydrocarbons, substantially all of which boil below the maximum boiling point of gasoline and above the boiling point of methane, to conversion 35 conditions at high temperature and relatively high super-atmospheric pressure, passing the products of said conversion to a separating zone, separating in said zone a fraction consisting principally of gasoline and heavier liquids and a fraction 40 consisting principally of hydrocarbons containing from two to four carbon atoms in the molecule, subjecting said last-mentioned fraction to conversion conditions wherein the temperature is relatively high and the pressure relatively low 45 and wherein these conditions are maintained for a time sufficient to produce aromatic hydrocarbons, cooling the products of this latter conversion and increasing the pressure thereon and discharging them together with additional hydrocarbon material of substantially the same boiling range into the said separating zone at a point 50 below the point of withdrawal of the fraction consisting principally of hydrocarbons containing from two to four carbon atoms in the molecule, separating the products of this latter conversion into fractions similar to those of the former conversion and discharging the combined 55 fractions from said separating zone.
